SASH

Joseph Martisius, Grand Rapids, Mich.

Application November 18, 1938, Serial No. 241,259

7 Claims. (Cl. 189—76)

My invention relates to windows, and has among its objects and advantages the provision of an improved sash.

An object of my invention is to provide a sash in which three rails are pivotally connected and a fourth rail detachably connected with two rails to permit removal of said one rail and adjustment of the other rails about their pivotal axes for opening the sash to facilitate installation and replacement of the glass pane.

Another object is to provide a demountable sash embodying two glass panes arranged in spaced relation to provide an air space in the sash.

Another object is to provide a sash which may be constructed of metallic rails together with means for cushioning the glass and to provide an effective seal between the glass and the metallic parts.

Another object is to provide a metallic sash construction embodying novel means for effecting a weather seal between the meeting rails of the upper and lower sashes.

In the accompanying drawings:

Figure 1 is an elevational view of a sash embodying my invention;

Figure 2 is a top plan view of the corner of the upper sash rail broken away for the sake of clearness;

Figure 3 is a sectional view along the line 3—3 of Figure 2;

Figure 4 is a sectional view along the line 4—4 of Figure 3;

Figure 5 is a perspective view illustrating the corner unit and a portion of the side rail associated therewith with the parts separated for the sake of clearness;

Figure 6 is a perspective view of a portion of the upper sash rail and the associated corner piece with the parts separated for the sake of clearness;

Figure 7 is a bottom plan view of one corner of the lower sash rail with certain parts broken away for the sake of clearness;

Figure 8 is a sectional view along the line 8—8 of Figure 7;

Figure 9 is a perspective view of one of the side rails with its corner part detached for the purpose of illustration;

Figure 10 is a perspective view of one end of the lower sash rail with its corner part detached for the sake of clearness;

Figure 11 is a perspective view of the corner housing for the lower corners of the sash rails;

Figure 12 is a transverse sectional view of the

meeting rails of two sashes illustrating the weather seal; and

Figure 13 is a sectional view along the line 13—13 of Figure 12.

Figure 14 is a top plan view of the connecting member shown in Figure 5, a portion being broken away.

Figure 15 is an elevation view of the connecting member shown in Figure 9.

10 In the embodiment selected to illustrate my invention, the sash 10 comprises a lower sash rail 12, side rails 14 and the upper cross rail 16. Side rails 14 are identical in construction and operation so that the description of one will apply to both. The rail 16 is detachably connected with the side rails 14, while the latter are pivotally connected at 18 with the rail 12 to permit the side rails to be pivoted outwardly and downwardly for releasing the glass 20 or in opposite directions for installation of the glass.

Figures 2 to 6 illustrate the corner construction of the top rail 16 and one of the side rails 14. Top rail 16 is illustrated in connection with the lower sash of a two-sash window. Specifically, 25 the rail 16 comprises metallic side walls 22 and 24 interconnected through the medium of a bottom wall 26 illustrated in Figures 3, 6 and 12. Bottom wall 26 is depressed to provide two spaced channels 28 for the reception of the upper margins of glass panes 20. Cushioning means in the nature of rubber-like material 32 is interposed between each pane and the walls of its respective channel 28.

30 Wall 22 includes a right-angular flange 34 arranged partly in overlapping relation with a similar flange 36 on the wall 24, but in spaced relation therewith, see Figure 12. Between the flanges 34 and 36 I mount a flange 38 having a hook 40 inside which the flange 34 is positioned. 35 Flange 34 is provided with an inverted U-shaped rib 42 terminating in a flange 44 extending across the flange 38 and provided with a hook 46 along its outer margin. A bowed spring 48 is connected with a loop 50 depending from the hook 40 and engaging the wall 24 for urging the hook 46 in the direction of the arrow 52. The lower rail 54 of the upper sash 56 is provided with a hook 58 reversed with respect to the hook 46 and arranged to lie inside the latter for effecting a weather-tight seal between the upper sash 56 and the lower sash 10. Spring 48 urges the hook 46 into pressure relation with the hook 58. Rib 42 constitutes a grip through the medium of which the hook 46 may be advanced against the tension of the spring 48 sufficiently far to bring the hook

in the clear of the hook 58 to permit raising of the lower sash or lowering of the upper sash.

It will thus be seen that the upper sash rail 16 is hollow and of generally rectangular configuration in cross section. Inside one end of the rail

16 I press a connecting member 60. Figure 6 illustrates the member 60 as including side walls 62 and 64 arranged to be pressed into frictional relation with the walls 22 and 24, respectively. Member 60 is formed of sheet metal of materially heavier gauge than the sheet metal making up the rail 16. The originally flat metallic strip comprising the member 60 is bent to provide inner side walls 66 interconnected by a bight 68 notched inwardly of one end at 70. The member is also fashioned to provide rectangularly shaped loops 72. The upper ends of the inner walls 66 and the loops 72 terminate in a common plane slightly below the upper edges of the side walls 62 and 64.

Member 60 is pressed into the rail 16 to a point where the ends 74 of the walls 22 and 24 terminate flush with the bights 76 interconnecting the side walls with the inner walls 70. At this time the ends of the channels 28 abut the bight 68. Walls 76 and 78 of the loops 72 are recessed at 80 for accommodating the channels 28. After the member 60 has been pushed home, the bights 82 of the channels 28 are struck partly into the loops 72, as at 84 in Figure 3, for fixedly connecting the member 60 with the rail. Figure 6 illustrates the wall 26 as terminating short of the ends 74 with the walls 22 and 24 flanged at 86 to extend underneath the lower edges of the side walls 62 and 64 of the member 60.

In Figure 5, I illustrate the upper end of one of the sash rails 14, which rail comprises sheet metal fashioned to provide side walls 88 and an interconnecting wall 90 bent to provide troughs 92 corresponding to the troughs 28 for the reception of the vertical margin of the glass associated with that side of the sash. The outer wall of the rail 14 comprises two flanges 94 terminating in spaced right-angular flanges 96. Flanges 96 may ride between parting strips associated with the window frame (not shown).

Within the upper end of the rail 14 I position a connecting member 98 which is fashioned of sheet metal considerably heavier gauge than the sheet metal from which the rail 14 is formed. Member 98 includes side walls 100 which terminate in loops 102 terminating in an inverted U-shaped element 104 fitting snugly between the inner side walls 66 of the member 60. The end 106 of the U-shaped element 104 lies against the inner face of the bight 68, while the end 108 terminates flush with the bights 76. The upper end of the rail 14 terminates substantially flush with the faces 110 of the member 98.

Faces 110 are cut away at 112, while the walls 114 of the loops 102 are cut away at 116, see Figure 14. When the member 98 is shoved home inside the rail 14, the channels 92 will be pressed between the walls 100 and the inner side walls 118 of the loops 102. With the member 98 properly assembled with the rail 14, the bights 120 are struck partly into the loops 102, as at 122 in Figure 3. Thus the member 98 will be effectively connected with the rail 14. Inner walls 66 of the member 60 are recessed at 124 to receive the end extensions of a pin 126 passing through the walls 106 and 108 of the U-shaped element 104. With the members 60 and 98 assembled, a key shank 128 is pressed between the side walls 106 and 108 with its hooked end 130

slipped through the slot 70 and hooked over the bight 68, as in Figure 3. Shank 128 includes a lug 132 arranged to be positioned inside the opening 134 in the bight of the U-shaped element 104.

Shank 128 includes a right-angular extension 136 having an opening 138 for the reception of the usual weight cord 140. Thus the weight cord pull effective on the key shank 128 will effectively support it in the position of Figure 3, at which time the member 60 is restrained from separation from the member 98. Lug 132 restrains the key shank 128 from relative longitudinal movement with respect to the walls 136 and 108. Pin 126 restrains the member 60 from relative longitudinal movement with respect to the member 98. Thus the two members are effectively connected into a unitary structure, but may easily be disconnected by merely re-20 moving the key shank 128.

Referring to Figures 7 to 11 inclusive, the lower end of the sash rail 14 is of the same construction as the upper end illustrated in Figure 5. Within the lower end of the rail 14 I position a connecting member 142 comprising sheet metal bent to provide a U-shaped element 144 connected with side walls 146 through the medium of right-angular runs 148. Side walls 146 are bent to provide loops 150. The walls 152 and 154 of the loops 150 are cut away at 156 to accommodate the channels 92 which are pressed between the side walls 146 and the inner walls 158. Figure 8 illustrates the bights 160 of the channels 92 as being struck inwardly of the loops 150, as at 162 to effectively connect the member 142 with the rail 14. The U-shaped element 144 of the member 142 is arranged to be frictionally positioned between the inner walls 162 of the member 164 connected with the lower sash rail 12. Inner walls 162 are connected with outer walls 166 through the medium of bights 168. The walls 166 have their upper edges terminating flush with the walls 162 which are located below the edges 170 of the side walls 166. The side walls 166 of the member 164 terminate in loops 172, and the walls 174 and 176 of the loops are cut away at 178 to accommodate the channels 178 of the rail 12.

Figure 7 illustrates the member 144 pressed 50 into the rail 12 to the position where its end 176 terminates substantially flush with the bight 180 interconnecting the inner walls 162. The bights 182 of the channels 173 are partly struck into the loops 176, as at 184 in Figure 8. Thus 55 the member 164 is fixedly related to the rail 12. Figure 10 illustrates the outer face of the rail 12 at 186, which outer face terminates in a depending U-shaped element 188 arranged to have overlapping relation with the vertical ledge 190 of the window sill 192 for sealing purposes. The inner wall 194 is fashioned to provide an inwardly extending flange 196 which facilitates manual manipulation of the sash.

U-shaped element 142 is positioned between the inner walls 162, at which time the edges 198 of the element 144 bear against the bight 180. The walls of the U-shaped element 144 are provided with aligned openings 200 for loosely receiving a pin 202 extending through openings 204 in the side walls 166 and riveted, as at 206 in Figure 7. Bight 180 is provided with an opening 208 for the reception of the reduced end 210 of a key bar 212 which is pressed between the pin 202 and the bight 214 of the U-shaped

element 144. The bar 212 fits snugly between the walls of the U-shaped element 144 and includes an under-cut 212 for the reception of the bight 214. With the key bar 212 in position, the bar 14 is latched against pivotal movement with respect to the bar 12. However, removal of the key bar 212 will permit the rail 14 to be pivoted about the pin 202 as an axis. In Figures 8 and 9, I have illustrated the U-shaped element 144 as being curved at 216, which curvature is concentrically related to the axis of the pin 202. Figure 8 illustrates the edges 198 as lying snugly against the bight 180. Thus the parts 142 and 164 will be positively latched against relative pivotal movement.

Channels 178 function in the same manner as the channels 28 of Figure 12. Key bar 212 is illustrated as being provided with an opening 218 which may be utilized for connection with a sash cord for an upper sash (not shown). In Figure 11, I illustrate a corner piece 220 for connection with the lower corners of the sash. Corner piece 220 includes a wall 222 terminating in a U-shaped flange 224 of the same configuration as the flange 188 and arranged to be brought into end-to-end abutting relation therewith when the corner piece is attached to the sash. The side wall 222 and the side wall 226 each includes an inset wall 228 which is arranged to ride on the upper edges of the walls 162 and 166.

Figure 8 illustrates the corner piece 220 in position, at which time the loops 230 lie between the upper edges of the narrow runs of the walls 162 and 166 and the right-angular runs 148 of the member 142. The U-shaped element 232 of the corner piece 220 is aligned with the flanges 96 on the rail 14. The wall 234 of the connecting member 220 is slotted at 236 so as to provide accommodation for the corner 238 of the U-shaped element 144 as it is pivoted about the pin 202 as an axis.

Between the two glass panes 20 I position cross rails 240 for ornamental purposes. The lower ends of the two vertical rails abut the wall 242 of the rail 12, the upper ends of the cross rails abut wall 26 of the upper sash rail 16, while the ends of the horizontal cross rails abut the walls 90 of the sash rails 14.

It will thus be seen that I have provided a window sash embodying two glass panes so arranged as to provide an effective air space therebetween. The outer margins of the glass panes are effectively sealed with respect to their associated sash rails. The glass panes have weather sealing relation with the sash rails, and the glass panes and the sash rails are effectively connected without the aid of glazier's points, putty and the like. The panes are quickly installed by merely first positioning the panes in proper connected relation with the lower sash rail 12 and pivoting the sash rails 14 into position. The upper sash rail 16 is then placed in position and keyed. The sash is then ready for use.

Without further elaboration, the foregoing will so fully illustrate my invention that others may, by applying current knowledge, readily adapt the same for use under various conditions of service.

I claim:

1. In a window sash, first and second hollow sheet metal rails, a first connecting member inserted in one end of the first rail and fixedly related thereto and a second connecting member inserted in one end of the second rail and fixedly related thereto, said first connecting member having a U-shaped element provided with a slot

5 in its bight and a second slot formation, said second connecting member having a U-shaped tongue adapted to be inserted in said U-shaped element to fit snugly therein and against said bight, pin means carried by said tongue for insertion in said slot formation to hold the tongue firmly against said bight, a shank inserted through said tongue to lie against the bight thereof and having an end inserted through said slot 10 for engagement with the bight of the U-shaped element to restrain the tongue from withdrawal with respect to the U-shaped element, and a window weight line connected with said shank to hold the latter in position against the bight of the tongue.

2. In a window sash, first and second hollow sheet metal rails, a first connecting member inserted in one end of the first rail and fixedly related thereto and a second connecting member inserted in one end of the second rail and fixedly related thereto, said first connecting member having a U-shaped element provided with a slot in its bight and a second slot formation, said second connecting member having a U-shaped tongue adapted to be inserted in said U-shaped element to fit snugly therein and against said bight, pin means carried by said tongue for insertion in said slot formation to hold the tongue firmly against said bight, a shank inserted through said tongue to lie against the bight thereof and having an end inserted through said slot for engagement with the bight of the U-shaped element to restrain the tongue from withdrawal with respect to the U-shaped element, a window weight line connected with said shank to hold the latter in position against the bight of the tongue, the bight of said tongue being provided with an opening, and a lug on said shank extending into said opening to key said shank.

3. In a window sash, first and second hollow sheet metal rails, a first connecting member inserted in one end of the first rail and fixedly related thereto and a second connecting member inserted in one end of the second rail and fixedly related thereto, said first connecting member having a U-shaped element provided with a slot in its bight and a second slot formation, said second connecting member having a U-shaped tongue adapted to be inserted in said U-shaped element to fit snugly therein and against said bight, pin means carried by said tongue for insertion in said slot formation to hold the tongue firmly against said bight, a shank inserted through said tongue to lie against the bight thereof and having an end inserted through said slot for engagement with the bight of the U-shaped element to restrain the tongue from withdrawal with respect to the U-shaped element, and a window weight line connected with said shank to hold the latter in position against the bight of the tongue, said first and second connecting members being detachable one from the other when said shank is removed.

4. In a window sash, first and second hollow sheet metal rails, a first connecting member inserted in one end of the first rail and fixedly related thereto and a second connecting member inserted in one end of the second rail and fixedly related thereto, said first connecting member having a U-shaped element provided with an opening in its bight, said second connecting member having a U-shaped tongue positioned inside the U-shaped element and pivotally connected therewith, and a key bar having an end inserted 70 through said opening and cooperable with the

bight of the tongue for restraining the first and second connecting members from relative pivotal movement, said key bar being removable to permit relative pivotal movement of said U-shaped element and U-shaped tongue.

5. In a window sash, first and second hollow sheet metal rails, a first connecting member inserted in one end of the first rail and fixedly related thereto and a second connecting member inserted in one end of the second rail and fixedly related thereto, said first connecting member having a U-shaped element provided with an opening in its bight, said second connecting member having a U-shaped tongue positioned inside the U-shaped element, a pin cooperating with said U-shaped tongue and the U-shaped element for pivotally connecting the first and second connecting members, and a key bar inserted between said pin and the bight of the tongue and extending into said opening for keying the first and second connecting members against relative pivotal movement, said key bar being removable to permit relative pivotal movement of said U-shaped element and U-shaped tongue.

6. In a window sash, first and second hollow sheet metal rails, a first connecting member inserted in one end of the first rail and fixedly related thereto and a second connecting member inserted in one end of the second rail and fixedly related thereto, said first connecting member having a U-shaped element provided with a slot in its bight and a second slot formation, said second connecting member having a U-shaped tongue adapted to be inserted in said U-shaped element to fit snugly therein and against said bight, pin means carried by said tongue for insertion in said slot formation to hold the tongue

firmly against said bight, a shank inserted through said tongue to lie against the bight thereof and having an end inserted through said slot for engagement with the bight of the U-shaped element to restrain the tongue from withdrawal with respect to the U-shaped element, a window weight line connected with said shank to hold the latter in position against the bight of the tongue, certain portions of said first and second members extending beyond their respective rails, and a sheet metal cap adapted for detachable connection with the exposed portions of the first and second connecting members.

7. In a window sash, first and second hollow sheet metal rails, a first connecting member inserted in one end of the first rail and fixedly related thereto and a second connecting member inserted in one end of the second rail and fixedly related thereto, said first connecting member having a U-shaped element provided with an opening in its bight, said second connecting member having a U-shaped tongue positioned inside the U-shaped element and pivotally connected therewith, a key bar having an end inserted through said opening and cooperable with the bight of the tongue for restraining the first and second connecting members from relative pivotal movement, said key bar being removable to permit relative pivotal movement of said U-shaped element and U-shaped tongue, certain portions of said first and second connecting members extending beyond their respective rails, and a sheet metal cap adapted to be connected with the exposed portions of said first and second members for enclosing the same.

JOSEPH MARTISIUS.
